US0D1019740S

(12) **United States Design Patent** (10) **Patent No.:** **US D1,019,740 S**
(45) **Date of Patent:** **** Mar. 26, 2024**

(54) **CAMERA HOUSING**

- (71) Applicant: **GoPro, Inc.**, San Mateo, CA (US)
(72) Inventors: **Daniel J. Coster**, Oakura (NZ); **Bessy Liang**, San Jose, CA (US); **Huy Phuong Nguyen**, Alpine, UT (US); **John George Muhlenkamp, IV**, Brisbane, CA (US); **Jordan Todd**, Piedmont, CA (US)
(73) Assignee: **GoPro, Inc.**, San Mateo, CA (US)
(**) Term: **15 Years**
(21) Appl. No.: **29/861,342**
(22) Filed: **Nov. 29, 2022**

Related U.S. Application Data

- (60) Division of application No. 29/842,487, filed on Jun. 14, 2022, now Pat. No. Des. 978,953, which is a continuation of application No. 29/805,978, filed on Aug. 31, 2021, now Pat. No. Des. 957,503, which is a division of application No. 29/771,317, filed on

(57) **CLAIM**

The ornamental design for a camera housing, as shown and described.

DESCRIPTION

FIG. 1 is a top, front, and right side perspective view of a camera housing showing our new design;
FIG. 2 is a bottom, rear, and right side perspective view thereof;

FIG. 3 is a top, rear and left side perspective view thereof;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a top plan view thereof; and,

FIG. 9 is a bottom plan view thereof.

The broken lines depict portions of the camera housing in which the design is embodied that form no part of the claimed design. The dash-dot broken lines denote the boundary of the claim and form no part of the claimed design.

1 Claim, 8 Drawing Sheets

Related U.S. Application Data

Feb. 22, 2021, now Pat. No. Des. 929,489, which is a division of application No. 29/705,667, filed on Sep. 13, 2019, now Pat. No. Des. 911,411.
